(57) **CLAIM**

We claim the ornamental design for a computer monitor frame board having decorative edge, erasable surface for notes, and pressure adhesive back, as shown and described.

DESCRIPTION

FIG. 1 is a perspective view of a computer monitor frame board having decorative edge, erasable surface for notes, and pressure adhesive back showing our new design in use; the broken lines depict environmental structure for illustrative purposes only and form no part of the claimed design; FIG. 2 is a front elevational view thereof; FIG. 3 is a rear elevational view thereof; FIG. 4 is a left side elevational view thereof, the right side elevational view being a mirror image thereof; FIG. 5 is a top plan view thereof; and, FIG. 6 is a bottom plan view being identical thereof.
